UNITED STATES PATENT OFFICE.

HADLEY P. FAIRFIELD, OF WEST MEDFORD, MASSACHUSETTS.

MACHINE FOR UNITING THE SOLES AND UPPERS OF BOOTS OR SHOES.

SPECIFICATION forming part of Letters Patent No. 329,031, dated October 27, 1885.

Application filed February 24, 1885. Serial No. 156,708. (No model.)

To all whom it may concern:

Be it known that I, HADLEY P. FAIRFIELD, of West Medford, county of Middlesex, State of Massachusetts, have invented an Improvement 5 in Machines for Uniting Soles to Uppers, of which the following description, in connection with the accompanying drawings, is a specification, like letters on the drawings representing like parts.

10 This invention has for its object the production of a machine in which the metal fastening employed may be riveted or clinched at both ends.

15 My invention is especially applicable for clinching that class of fastening which is cut from a long compound wire, or such a wire composed of two or more wires twisted together, or from a tube-like wire surrounding a flexible core.

20 The machine herein described is intended to be an improvement on the class of machine represented in United States Patent No. 135,681, wherein an independent clinching device is employed.

25 My improved machine contains a compound driver composed essentially of a rod and a closely-fitting tube which surrounds it, each one being actuated independently for part of the driving-stroke. The wire to be driven is 30 cut off in lengths measured to conform to the thickness of the stock, and each length as cut off is taken by a carrier and placed in the line of movement of the center rod or portion of the driver, the latter driving the fastening 35 from the carrier into and through the tubular part of the compound driver and into and through the stock, and into a cavity below it in the horn, which latter is provided with a hammer that takes the place of the clinching 40 device shown in the said patent, the said hammer being operated automatically by means of mechanism within the horn, the hammer being actuated after the fastening has been driven. The lower end of the tubular 45 part of the compound driver is made to stand normally at but a short distance above the bottom of the channel in the stock, in which channel rests the usual nose, and the center rod of the compound driver in its descent 50 drives the upper end of the fastening flush

with the lower end of the tubular part of the driver, and both the center part and the said tubular part then remain stationary and act as an abutment or stop for the upper end of the fastener, while the hammer in the horn 55 operates, as described, to clinch the driven end of the fastener, and thereafter the center rod and tubular part of the compound driver descend together to clinch the upper end of the fastening, the hammer in the horn acting at 60 such time as an abutment for the lower end of the fastener.

One part of my invention consists in a two-part or compound driver, and also in the combination with the same of a hammer or clinching 65 device in the horn.

Figure 1, in side elevation, represents a machine embodying my invention, a part of a shoe being shown upon the horn, the driving-pulleys shown at the left of Fig. 2 being omitted. Fig. 2 is a front elevation thereof with the shoe removed. Fig. 3 is a vertical central section of Fig. 2, the treadle to depress the horn for the application of the shoe thereto being omitted. Fig. 4 is a partial 75 top view. Fig. 5 is a sectional detail of the lever and connected parts for operating the tubular part of the compound driver; Fig. 6, a detail of the cutters and their actuating device. Fig. 7 is a detail of the carrier for 80 the fastener, together with a cross section of the drivers. Fig. 8 is a sectional detail of the lever to lift the nose-piece; Fig. 9, a detail top view of the horn broken out; Fig. 10, a section in the line $x'x'$, Figs. 1 and 3, looking 85 down; and Fig. 11 is an under side view, looking upward of the nose and the lower end of the compound driver.

The frame-work A, of suitable shape to sustain the working parts, has a main shaft, A', 90 having upon it a fast pulley, A², and a loose pulley, A³. The shaft A' has fast upon it a triple cam, B, cams C, D⁴, and E.

The tubular portion A⁴ of the frame-work receives within it the sleeve a, to the lower 95 end of which is attached the tube a' of the compound driver, and inside the sleeve a is placed the driver-rod a², to the lower end of which is attached the center rod, a³, of the compound driver. The lower end of the tubu- 100

lar portion A⁴ of the frame-work has fitted upon it the upper end of the nose-carrier D, which is made vertically movable thereon by means of the arm D', projected from the rock- 5 shaft D², the latter having a second arm, D³, (shown by dotted lines in Fig. 1, and in section in Fig. 8,) the said arm having a roller-stud, 3, which is acted upon by the cam D⁴. The front end of the said arm D' is forked to em- 10 brace a pin or stud, 2, of the nose-carrier D, provided at its lower end with the nose D⁵, the latter being attached to the nose-carrier by means of the two screws D⁶ D⁶, (see Fig. 11,) the said nose being oblong in shape externally, 15 as shown in said Fig. 2, so that the nose can enter the channel and hold the flap up, as shown in Fig. 3.

The driver-rod a² of the compound driver is provided at its upper end with a cross-head, 20 a⁵, which is held in place, as shown, by a nut, a⁶. This cross-head has joined to it at each side the driver-rod a link, c', each link being in turn jointed to the front end of a forked lever, c², attached to a rock-shaft c³, the said 25 shaft having a second arm, c⁴, which at its other end is provided with a roller-stud that is acted upon by the cam C, the said roller-stud entering a cam-groove, (shown in dotted lines in Fig. 1,) the said groove being of proper 30 shape to operate the driver-rod positively in both directions of its movement, the descending stroke thereof being divided into two stages, as before stated.

The sleeve a, carrying the tube a', which 35 forms part of the compound driver, has at each side a pin or stud, 7, which is embraced by the forked front end, b², (see Fig. 5,) of a lever, B', mounted on a fulcrum, b³, and having a rearwardly-extended arm, b⁴, provided with a 40 roller-stud, b⁵, which enters a cam-shaped groove in the triple cam B, (see Fig. 3,) the said cam moving the lever B' to reciprocate the tubular part a' of the compound driver, so that its end shall move in unison and be 45 flush with the lower end of the center rod, a³, during such time as the upper end of the fastening is being clinched in the channel.

The wire to be used for the production of 50 the fastenings will preferably be such as represented in United States Patent No. 110,431 and No. 193,690; but I desire it to be understood that I may employ any other usual wire or fastening material.

The wire f is passed through a feeding-slide, 55 f', placed loosely in a guide, f², attached to the frame of the machine, the feeding-slide being reciprocated in the said guide by means of a rod, f², held loosely in the cross-block f³, attached to the forked arms c², the lower end 60 of the said rod f² being pivoted to a dog, 8, pivoted at 9 upon ears extended from the feeding-slide f', (see Fig. 3,) so that as the arm c² is thrown down in driving a fastening the cross-block f³, by its action on the spring 10-- 65 the latter resting on a nut, 13, fast on the rod-- causes the dog to first turn and impinge against the wire, and thereafter, as the rod descends,

the dog carries the wire down, and with it the feeding-slide to feed the wire into the carrier, to be described.

The downward stroke of the slide f', after 70 the dog engages the wire, will be variable according to the variation in the thickness of the stock and the position of the horn vertically.

The extent of the downward stroke of the slide and the length of the wire protruded into the carrier will be determined by an arm, e, on a rocker-shaft, e', against which arm the lower end of the feed-slide strikes, after which, 80 in the further downward movement of the arm e² and cross-block f³, the spring 10 is compressed. The rock-shaft e' has at the right-hand end of the machine a second arm, e², (shown in dotted lines, Fig. 1, and partly in 85 full lines, Fig. 3,) which arm is connected loosely to a rod, e³, loosely connected at its lower end with an arm, e⁴, of a rocker-shaft, e⁵, the said shaft having attached to it a tri-armed lever, e⁶, one arm of which has a face, as at 14, to 90 impinge against a face, 15, of the feed-measuring lever F, pivoted at F' on the frame-work, the said lever being forked at its front end, and provided with anti-friction rollers F², which rest against the collar F³ on the horn-shaft F⁴, the spring F⁵ acting to keep the rollers in contact with the said collar, and also to 95 keep the horn pressed up toward the nose.

When the nose is forced down into the channel to hold the shoe prior to driving each fastening, the horn is depressed more or less, according to the thickness of the stock on the horn under the nose, and the feed-measuring lever is turned, changing the position of the face 15 of the said lever, so as to sooner or later 100 arrest the end 14 of the tri-armed lever e⁶, or to stop it in the position necessary to enable the feed of the wire to be measured to the thickness of the stock. The end 14 of the tri-armed lever is lifted, just before feeding the 105 wire for each fastening, and while the feed-measuring lever is being put into position, by the projection 16 of the triple cam B, which projection acts upon a roller, g⁴, at the upper 110 end of the rod g¹, passed through fixed guides g²; but as soon as the projection 16 passes the roller the spring g, resting on one of the guides g³, and acting against the collar g², moves the rod g¹ and throws the end 14 of the tri-armed lever against the end 15 of the measuring-lever. 115

As the tri-armed lever is moved, as last described, the arm e⁴, connected with the shaft e⁵ through rod e³, arms e², and rock-shaft e', places the arm e in position to sooner or later 120 stop the downward movement of the feed-slide f'. As the tri-armed lever e⁶ is stopped in one or another position by the face 15 of the feed-measuring lever, the arm e, in operative connection with the said lever, is left in a position correspondingly changed, so that the slide f' 125 is stopped sooner or later, so that the length of wire fed into the carrier for the production of the next fastening will be automatically 130 varied in accordance with the thickness of the

stock. As the arm c^2 is lifted, the cross-block f^3 acts against the nut 12 and lifts the slide f' , the dog 8 at such time slipping over the wire, the latter being held by the detent 17. The 5 cutting mechanism to cut off the wire is shown best in Fig. 6, it consisting of two levers, h^1 , pivoted at h' , each lever carrying at one end a blade, h^2 , and at its other end a roller-stud, the said levers being operated once at each 10 rotation of the cam B by means of projections h^4 at opposite sides of the said cam, the said projections acting as a wedge between the said roller-studs h^3 .

The carrier or transerrer for the fastening 15 cut from the wire, and best shown in Figs. 7 and 3, is composed of two spring-arms, m^1 , connected to a slide-block, m' , having a rearward extension, m^2 , and an upward extension, 18, the rearward extension passing through a 20 spiral spring, 19, and thence through a hole in the frame-work A, where it is provided with the nuts 20, which regulate the forward position of the said carrier when under the control of the said spring, the carrier being 25 moved backward by the lever n , mounted loosely on the rock-shaft c^3 , the said lever being acted upon by the screw 21 in the cross-block f^3 , attached to and moving with the arms c^2 .

30 The forward end of each arm of the carrier (see Fig. 7) is concaved, as at m^3 , forming a pair of spring-jaws, with a space between of suitable size to receive the wire as the latter is fed from the guide f^2 , as is the case when 35 the carrier is held back, as in Fig. 3. After the cutters are operated to sever the wire and leave in the carrier or between its jaws a piece of wire of the length desired for the next fastening to be driven, the arm c^2 will be 40 raised, lifting the driver-rod a^2 and the center rod, a^3 , of the compound driver, which thus relieves the lever n from the pressure of the screw 21, permitting the spring 19 to move the carrier with its fastener forward, the front end 45 of the carrier entering the space 22 and placing the fastening or short length of wire in line with the end of the center rod of the compound driver, so that as the latter descends it will strike the upper end of the fastening 50 and drive it from the carrier down through the tubular part a' of the compound driver and into the "stock" o , the latter being the term employed by me to designate the sole of the boot or shoe, the stock resting on the horn and being 55 channeled, as shown, in the line in which the fastenings are to be driven, the nose D^5 entering the said channel, as shown in Fig. 3. The center rod, a^3 , of the driver descends between the jaws of the carrier and drives the 60 fastener into the stock until the upper end of the fastener comes flush with the lower end of the tubular part a' of the compound driver, when the descent of the center rod is temporarily arrested, the lower end of the fastening 65 at such time resting in a recess in the horn G. While the two parts of the compound driver rest with their ends flush with each other, the

hammer H, pivoted in the horn at H' , is operated, as will be described, to rivet or clinch the lower end of the wire, the compound driver 70 then acting as an abutment; but as soon as the hammer clinches the said lower end of the fastening, it remains at rest, while the compound driver, its two parts having their ends flush, is thrown farther down, and at such 75 second part of the divided descent of the compound driver to clinch or upset the upper end of the fastening in the channel formed in the stock the hammer H acts as an abutment against the lower end of the fastening, the 80 hammer being held by the spring r .

The carrier for the fastener must be drawn back while the center rod of the driver is descending through it. This is done by the action of the screw 21 on the lever n , the split 85 or jaw-like front end of the carrier being separated as the carrier is pushed back laterally away from the center rod, a^3 by the wedge o' , (see Fig. 7,) supported by the spring o^2 , the wedge, when the driver-rod is descending in 90 the space m^3 , occupying a position in the space 23 between the arms m^1 .

The thin edge of the wedge is directed toward the front of the machine, and as the carrier is driven back its shouldered portion between the spaces 23 and 24 acts against the wedge, and the latter forces the jaws apart, 95 permitting the part m^3 to separate and not strain the center rod of the driver.

When the carrier is moved forward to transfer a fastening into position to be struck by the center rod of the driver, or forward from the position Figs. 3 and 7, the under side of the carrier, striking the downwardly and backwardly inclined rear edge of the wedge, depresses the same, compressing the spring o^2 under it, the wedge being thrown up quickly as soon as the space 23 arrives in position above it.

The lower arm of the tri-armed lever, by 100 means of a forked rod, p , is made to engage a pin, p' , of the lever p^3 , pivoted at p^2 , forked at its front end to embrace the hammer-operating rod p^5 , and having rollers p^4 , which act upon the flange of and sustain the sleeve 115 p^6 , placed on the said rod p^5 loosely and free to slide in the guide p^7 . The rod p^5 between the top of the sleeve p^6 and the lower end of horn-stem F⁴, placed loosely in a guide, A⁸, of the frame, is surrounded by a spiral spring, 120 r , which, acted upon by the end of the horn-stem, keeps the collar of the sleeve down upon the lever p^3 or the rolls p^4 , the lower end of the sleeve p^6 acting on the nut p^{10} , causing the rod p^5 to descend with the sleeve. 125

The measuring-lever at one side is provided with a horn-rod locking device, r' , made as a hook, pivoted at r^2 , the hook engaging a pin or projection, r^3 , on the lever p^3 . The lever r' at its upper end is joined by link r^4 130 with a lever, r^5 , pivoted at r^6 . The lever r^5 at its upper end has a roller, r^7 , which is acted upon by a projection (see Fig. 1) of the cam E as the fastening is driven through the stock

into the position Fig. 3, such movement of the lever effecting the release of the catch from the projection r^3 and enabling the spring r , acting on the sleeve p^6 , to pull the rod p down, 5 causing the slotted head 26 of the rod p^5 , (see Figs. 3 and 10,) acting on the lower end, 25, of the lever s , pivoted at s' in the horn, and engaged at its upper end with the lower notched end of the hammer, to quickly throw 10 the face of the hammer against the lower end of the fastening standing in the cavity at the top of the horn, thus clinching the same at the inner side of the inner sole, u , the compound driver standing at such time as an abutment 15 against the upper end of the fastener, as shown in Fig. 3, where the fastener is marked 27, and the hammer is thereafter held by the spring r face against the lower end of the fastener, forming an abutment, while the compound 20 driver, with the lower end of its two parts flush, descends together to clinch the upper end of the fastener in the channel t of the outer sole, t' .

The horn may be lowered by placing the 25 foot on the lever t' , (shown in Figs. 1 and 2,) which is attached by link t^3 with the measuring-lever F , the spiral spring t^4 , interposed between the guide p^7 and the lever F , keeping the horn normally pressed upward.

30 I claim—

1. In a machine for uniting soles to uppers, a horn to support the stock, combined with a compound driver composed of a movable rod and a movable tube arranged outside of the 35 rod, the tube acting as a guide for the fastener, located above but not in contact with the stock, the rod striking the end of the fastener after it is cut off and driving it partially into the stock, leaving the upper end of the fastener 40 flush with the lower end of the said tube, substantially as described.

2. The horn and its hammer, combined with the compound driver composed of an independently-movable rod and tube, the latter 45 guiding the fasteners, while the former drives the fastening through it into the stock, with its upper end flush with the end of the tube, substantially as described.

3. The horn and its hammer, and the compound driver composed of the independently-movable center rod and tube, combined with means, substantially as described, to operate the said hammer and the driver, imparting to the latter a divided movement, as set forth, whereby the center rod of the compound driver 50 first drives the fastening through the tubular part of the driver into the stock, with the upper end of the fastening flush with the end of the said tubular part, in which position the driver remains while the hammer acts to clinch 55 the lower end of the fastening, the hammer then in turn remaining at rest, forming an abutment for the lower end of the fastening, while the two parts of the compound driver descend and clinch the upper end of the fastening in the channel cut in the stock, substantially as described.

4. The sleeve, its attached tube, the driver-rod, and the attached center rod, and the part A^4 of the frame, combined with the independently-movable nose and nose-carrier, and with means, substantially as described, to operate the said parts.

5. In a machine for uniting soles to uppers, a driver-bar and attached rod having a 75 divided downward movement, as described, to at first partially drive a fastening and then remain at rest, while the lower end of the fastening is clinched, and then by its further downward movement to clinch the upper end 80 of the fastening, in combination with a horn and a hammer to clinch the lower end of the fastening and act as an abutment for the lower end of the fastening, of which the upper end of the latter is being clinched by the said rod, 85 substantially as described.

In testimony whereof I have signed my name to this specification in the presence of two subscribing witnesses.

HADLEY P. FAIRFIELD.
